UNITED STATES PATENT OFFICE

148,126

DESIGN FOR A JEWELRY CLASP

Paul Bardach, Providence, R. I.

Application June 19, 1947, Serial No. 139,807

Term of patent 7 years

(Cl. D45—4)

To all whom it may concern:

Be it known that I, Paul Bardach, a citizen of the United States, residing at Providence in the county of Providence and State of Rhode Island, have invented a new, original, and ornamental Design for a Jewelry Clasp, of which the following is a specification, reference being had to the accompanying drawing, constituting a part thereof.

Fig. 1 is a front view of a jewelry clasp showing my novel design; and

Fig. 2 is a side view thereof.

I claim:

The ornamental design for a jewelry clasp, substantially as shown.

PAUL BARDACH.
